UNITED STATES PATENT OFFICE.

JOHN G. ROSS, OF SOUTH EASTON, MASSACHUSETTS, ASSIGNOR TO UNITED SHOE MACHINERY COMPANY, OF PATERSON, NEW JERSEY, A CORPORATION OF NEW JERSEY.

CHANNELING-MACHINE.

1,029,227.

Specification of Letters Patent. Patented June 11, 1912.

Application filed August 3, 1905, Serial No. 272,528. Renewed January 2, 1908. Serial No. 470,531.

To all whom it may concern:

Be it known that I, JOHN G. Ross, a citizen of the United States, residing at South Easton, in the county of Bristol and State 5 of Massachusetts, have invented certain new and useful Improvements in Channeling-Machines; and I do hereby declare the following to be a full, clear, and exact description of the invention, such as will enable 10 others skilled in the art to which it appertains to make and use the same.

The present invention relates to improvements in channeling machines.

In the manufacture of welted boots and 15 shoes the insole is usually provided with a channel in its marginal portion and the edge of the sole is split to form a lip for the reception of stitches.

The present invention relates to improvements 20 in machines for performing one or both of these operations upon a sole or an insole, and its object is to simplify and improve the construction of such machines in the respects hereinafter pointed out.

25 Other objects of the invention will be noted in connection with the description of the illustrated embodiment thereof.

To the above ends the invention consists 30 in the improved channeling machine hereinafter described and defined in the claims.

In the drawings illustrating the preferred 35 form of the invention Figure 1 is a front elevation of the machine; Fig. 2 is a left hand side elevation; Fig. 3 is a right hand side elevation; and Fig. 4 illustrates the manner in which the knives operate upon the insole.

The illustrated embodiment of the machine comprises as its operating instruments 40 a channeling knife 1 and an edge-slitting knife 2, together with a work support 3 and suitable mechanism for actuating these parts to cause them to feed the work and cut the channel and the slit. The 45 work support 3 is in the form of a truncated cone mounted on a stem 4 journaled in a bracket 5 on the frame of the machine. The work support is mounted unyieldingly, the necessary adjustments for different thicknesses 50 of work being embodied in the parts by which the knives are supported and actuated. The work support, therefore, forms a rigid support for the work and cannot yield to the thrust of the channeling knife. 55 The work support performs the operation

of feeding the work, being rotated by means of a ratchet 6 fixed to the work support and actuated by a slide 7 mounted on the frame of the machine. The forward end of the slide is held yieldingly in engagement with the ratchet by a spring 8, and the slide is reciprocated longitudinally by means of a lever 9 journaled in the frame of the machine and connected with the slide by a pin-and-slot connection, as shown in Fig. 2. 60 The lever 9 carries at its upper end a cam roll engaging a cam 10 upon the shaft 11 of the machine, and the cam roll is held against the cam 10 by a spring 12 connected with the lever 9 and the frame of the machine. 70 To prevent retrograde movement of the work support a friction washer 13 is pressed against the stem 4 of the work support by a screw 14.

The channeling knife is arranged to vibrate transverse with respect to the line of feed so as to cut the channel by a succession of chopping cuts which overlap to form a continuous channel. The knife is adjustably fixed as shown in Fig. 3, by means of screws 75 15 engaging a horizontal slot in the knife, to a knife carrier 16 which is mounted on a lever 17 by means of screws 18 engaging a slot in the knife carrier so as to permit vertical adjustment of the knife carrier. The 80 lever 17 is pivoted at 19 upon a head 20 so as to have an oscillating movement, and the lever and channeling knife are actuated by mechanism comprising a link 21 pivotally connected with an arm 22 adjustably fixed 85 to a slide 23 having a bearing on the frame of the machine and carrying a cam roll 24 engaging a cam path in a cam 25 on the shaft 11.

In order that the channeling knife may 90 always cut a channel of the same depth however the thickness of the work may vary, the head 20 is arranged to rise and fall, carrying the pivot 19 and the parts mounted thereon with it, and such rising and falling 95 movements are controlled by a presser foot 26 fixed to the head 20 and bearing upon the surface of the work. The head 20 is adjustably connected by a horizontal shank 27 with an arm 28 pivoted at 29 on the frame 100 of the machine and pressed downward so as to hold the presser foot in engagement with the work by a spring 30 connected with the frame of the machine by an adjusting screw 31. The shank 27 is slotted at 50 and a 110

binding screw 51 passing through the slot fixes the shank in place. By means of an adjusting screw 52 passing through the head 20 into the arm 28 the head may be adjusted 5 horizontally when the binding screw 51 is loosened, and in this way the position of the center of oscillation of the knife carrier may be adjusted horizontally so as to vary the distance between the channel and the slit 10 and determine the thickness of the between substance. The link 21 connecting the lever 17 and the slide 23 permits rising and falling movements of the lever 17 and parts carried thereby without interference with the 15 vibrating movement transmitted to the channeling knife, and since the relation of the presser foot 26 and the pivotal support 19 of the channeling knife is fixed the knife cuts always to the same depth below the 20 presser foot, and thus its action is uniform whatever the thickness of the work. The vertical adjustment of the knife carrier 16 on the lever 17 in connection with the vertical adjustment of the presser foot permits 25 the distance between the channeling knife and the pivot 19 to be changed and in this way the center of oscillation of the knife carrier may be adjusted vertically and the radius of oscillation of the channeling knife 30 may be varied to vary the form of the channel which is cut, and the depth of the channel may be adjusted by moving the presser foot 26 vertically upon the head 20, the presser foot being for this purpose connected 35 adjustably to the head by screws 32 engaging slots in the shank of the presser foot, as shown in Fig. 3. It will be obvious that the form of the channel which is cut can also be varied by the horizontal adjustment of the 40 head 20 and transverse adjustment of the channeling knife 1 on the knife carrier 16. A horizontal adjustment of the head 20 followed by a transverse adjustment of the knife 1 changes the angle of the cut with relation to the adjacent surface of the work 45 support. In order to prevent accidental contact between the channeling knife and the work support when no work is in the machine a stop screw 33 is arranged to limit the downward movement of the arm 28. The edge-slitting knife 2 also operates by a 50 succession of reciprocations transverse to the line of feed so as to slit the soles by a series of overlapping cuts. The edge-slitting knife is mounted on a slide 34 having 55 bearings in a carrier 35 and it is actuated by a lever 36 pivoted on the frame of the machine and connected with the slide by a pin-and-slot connection. The upper end of the 60 lever 36 carries a cam roll engaging a cam 37 on the shaft 11, and the cam roll is held against the cam by a spring 38 connected with the lever 36 and the frame of the machine. 65 In order that the position of the slit in

the edge of the insole may be varied, means are provided for adjusting the distance between the edge-slitting knife and the surface of the work support. The carrier 35 is pivotally connected at 39 to the frame of 70 the machine and its forward end may be raised and lowered so as to change the path of movement of the edge-slitting knife. As it is usually desirable that the thickness of the feather may be constant, an adjustable 75 stop screw 48 is provided, against which the carrier 35 may rest during the operation of the machine, being drawn downward by a spring 44 connected with the carrier by a screw 45, so that the distance between the 80 edge-slitting knife and the work support remains constant as adjusted. If, however, it is desired to make the lip of the insole of constant thickness, it is necessary to determine the position of the edge-slitting 85 knife by the position of the upper surface of the work, and in order that this may be done when desirable a presser foot 40 is secured to the carrier by means of adjusting 90 screws 41 and 42 acting to draw the shank 95 of the presser foot against a pin 43 on the carrier 35. The presser foot is drawn against the surface of the insole by the spring 44 and maintains the edge-slitting knife at a constant distance from the surface since the carrier 35 is free to rise and fall with the presser foot. When the machine is operating in this manner the stop 100 screw 48 is lowered so as not to interfere with the movements of the carrier, but it may serve as a stop to prevent contact between the edge-slitting knife and the work support when there is no work in the machine.

An edge gage 46 for gaging the depth of 105 the cut produced by the edge-slitting knife is adjustably mounted on the carrier 35 by means of screws 47 engaging slots in the shank of the edge gage.

In the operation of the machine the work 110 is held by the operator upon the inner surface of the work support, being pressed thereagainst by the presser feet 26 and 40, and the rotation of the shaft 11 causes the knives to engage the work simultaneously 115 and then to simultaneously retreat therefrom, and while the knives are out of operative engagement with the work the work support is rotated through a small angle to feed the work for the next cut. As the 120 thickness of the work varies the presser feet cause the supporting and actuating mechanisms for the knives to rise and fall so that the paths of movement of the knives and the cuts produced thereby have always the 125 same position relative to the upper surface of the work.

A machine in which the channeling knife and the edge-slitting knife vibrate transversely to the line of feed has previously 130

been proposed, and it is not intended to claim such a machine broadly, the present invention being directed to the improved means for feeding and supporting the work and controlling the movements of the knives. The several adjustments of the channeling knife and its actuating and supporting mechanism permit the arrangement of the knife to cut a channel of any desired depth, form, and position. The use of a yielding support for the channeling knife permits the use of an unyielding work support and edge-slitting knife carrier, where it is desired to make the feather of constant thickness, whereby the construction of the machine is simplified, and it is new, so far as the applicant is aware, to mount a channeling knife vibrating transversely with respect to the line of feed upon a carrier arranged to yield in accordance with the thickness of the work, whether in combination with a fixed or a yielding work support.

The invention is not limited to the details of construction and operation described in connection with the illustrated embodiment thereof, but may be embodied in other forms broadly defined in the claims.

I claim—

1. A channeling machine having, in combination, a work support, a channeling knife vibrating transversely with respect to the line of feed during the channel cutting operation, a yielding presser foot bearing on the surface of the work opposite to the work support, and means for supporting and actuating the channeling knife connected with the presser foot so that the path of movement of the channeling knife is determined by the presser foot in accordance with varying thickness in the work, substantially as described.

2. A channeling machine having, in combination, a work support, a channeling knife vibrating transversely with respect to the line of feed, a yielding presser foot bearing on the surface of the work opposite to the work support, and a lever by which the channeling knife is supported and actuated, the lever being oscillated about a fulcrum connected with the presser foot so as to move in unison with the latter to conform to varying thickness in the work, substantially as described.

3. A channeling machine having, in combination, means for holding the work and slitting the edge thereof, a channeling knife vibrating transversely with respect to the line of feed during the channel cutting operation, a yielding presser foot bearing on the surface of the work, and means for supporting and actuating the channeling knife connected with the presser foot so that the path of movement of the channeling knife is determined by the presser foot in accord-

ance with varying thickness in the work, substantially as described.

4. A channeling machine having, in combination, a work support, a channeling knife and an edge-slitting knife vibrating transversely with respect to the line of feed, means for supporting and actuating the knives, and two independent yielding presser feet bearing against the surface of the work opposite to the work support and connected respectively with the supporting and actuating means for the knives so as to determine the paths of motion of the knives in accordance with variations in the thickness of the work, substantially as described.

5. A channeling machine having, in combination, means for supporting and feeding the work, a channeling knife arranged to vibrate transversely with respect to the line of feed, and a pivotally-mounted oscillating lever for supporting and actuating the channeling knife, the knife being adjustable longitudinally of the lever so as to vary the radius of oscillation of the knife, substantially as described.

6. A channeling machine having, in combination, a work support, an edge-slitting knife, means for maintaining the edge-slitting knife at a fixed distance from the work support, a channeling knife vibrating transversely with respect to the line of feed during the channel cutting operation, and yielding means for supporting and actuating the channeling knife arranged to vary the position of the knife according to the thickness of the work, substantially as described.

7. A channeling machine having, in combination, a channeling knife, an oscillating carrier therefor oscillating transversely with respect to the line of feed during the channel cutting operation, and means for vertically adjusting the center of oscillation of the carrier, substantially as described.

8. A channeling machine having, in combination, a channeling knife, an oscillating carrier therefor oscillating transversely with respect to the line of feed during the channel cutting operation, and means for adjusting horizontally the center of oscillation of the carrier, substantially as described.

9. A channeling machine having, in combination, a channeling knife, an oscillating carrier therefor oscillating transversely with respect to the line of feed during the channel cutting operation, and means for adjusting both vertically and horizontally the center of oscillation of the carrier, substantially as described.

10. A channeling machine having, in combination, a channeling knife, a lever for oscillating the knife during the channel cutting operation mounted on a movable ful-

crum, and means for actuating the lever connected thereto by connections arranged to permit the fulcrum to be moved without substantially affecting the oscillating movements of the lever and channeling knife, substantially as described.

11. A channeling machine, having, in combination, a channeling knife, an edge-slitting knife vibrating transversely to the line of feed, and means for determining the

position of the cut made by the edge-slitting knife from either side of the sole to make either the lip or the feather of constant thickness, substantially as described.

In testimony whereof I affix my signature, 15 in presence of two witnesses.

JOHN G. ROSS.

Corrections in Letters Patent No. 1,029,227.

It is hereby certified that in Letters Patent No. 1,029,227, granted June 11, 1912, upon the application of John G. Ross, of South Easton, Massachusetts, for an improvement in "Channeling-Machines," errors appear requiring correction as follows: In the heading to the printed specification and to each of the three sheets of drawings, date of renewal, for "Renewed Jan. 2, 1908" read *Renewed Jan. 2, 1909*; and page 1 of the printed specification, line 18, before the word "stitches" insert the article *the*, and line 76, for the word "transverse" read *transversely*; and that the said Letters Patent should be read with these corrections therein that the same may conform to the record of the case in the Patent Office.

Signed and sealed this 16th day of July, A. D., 1912.

[SEAL.]

C. C. BILLINGS,
Acting Commissioner of Patents.
